UNITED STATES PATENT OFFICE.

FRED L. MACKENZIE, OF BEVERLY, MASSACHUSETTS, ASSIGNOR TO UNITED SHOE MACHINERY CORPORATION, OF PATERSON, NEW JERSEY, A CORPORATION OF NEW JERSEY.

WORK SUPPORT.

1,417,540.

Specification of Letters Patent. Patented May 30, 1922.

Application filed August 1, 1918, Serial No. 247,732. Renewed July 16, 1921. Serial No. 485,349.

To all whom it may concern:

Be it known that I, FRED L. MACKENZIE, a citizen of the United States, residing at Beverly, in the county of Essex and Commonwealth of Massachusetts, have invented certain Improvements in Work Supports, of which the following description, in connection with the accompanying drawings, is a specification, like reference characters 10 on the drawings indicating like parts in the several figures.

This invention relates to work supports and to mechanism for controlling work supports, such for example, as those used in the 15 manufacture of boots and shoes, and has especial utility in machines for inserting fastenings. It will be understood, however, that the invention is applicable to other types of machines and is capable of utilization 20 in connection with other types of work supports.

In the manufacture of boots and shoes it is common practice to secure the heel seat of the sole of a shoe to the lasted shoe with 25 metallic or other suitable fastenings before the last is withdrawn from the upper. Frequently, also, spring and other kinds of heels are secured to the soles of shoes while the last is still within the shoe, and these 30 heels when so secured are often thereafter slugged or otherwise provided with protectors or ornaments while the shoe is still on the last. In successfully performing any 35 of these operations, before the last is removed from the shoe, it has been found advantageous to mount the last on a jack spindle provided with suitable means to engage and retain the last thereon. The machine in which a work support of this kind 40 is to be used commonly has a stationary work abutment against which the work is pressed during the fastening inserting operation. It is desirable that the work in all cases be clamped firmly during the 45 insertion of fastenings, for example, in the operation of heel seat nailing, in order to press the heel seat end of the outsole into close contact with the insole and folded-in margin of the shoe upper and to insure that the 50 fastenings will be fully and properly inserted and the shoe parts united in the most satisfactory manner.

Heretofore considerable difficulty has been encountered in securing uniform pressure on work during fastening inserting op-

erations owing in some instances to lack of uniformity in the positions, depths and conditions of the last pin holes in the lasts on which the work is mounted but more especially to differences in thickness of the 60 work, as for instance, in the heights of heels, to differences in the heights of lasts, and to other causes tending to a lack of uniformity in the work. In one class of machines commonly used for inserting fastenings in heel seats and in heels, adjustment of the work support to secure proper presentation of the work and proper release for feeding of the work has been effected by hand. Because of the conditions attendant 70 upon the presentation of work to the operating instrumentalities as outlined above, the application of proper clamping pressure on the work requires, theoretically at least, frequent adjustment of the work 75 support. As a matter of actual practice, however, the work support was adjusted only for shoes distinctly different in style or size from those last operated upon, or where the shoes were upon lasts of a different size or type. This practice followed naturally, since the time and effort necessarily expended in the manual adjustment of the work support rendered it a matter of such 80 inconvenience that the operative avoided it 85 wherever possible. Moreover, there being no measuring means for the work, the degree of adjustment and therefore of the clamping pressure effected depended altogether upon the skill and judgment of the 90 operative. For this reason also, no attempt was made to adjust for anything but marked variations in the characteristics of the work.

It is an object of the present invention 95 to provide an improved work support mechanism that will automatically measure the work and ensure the application of proper pressure on work of varying thickness during the operation of fastening inserting or other mechanism thereon.

In one aspect of the invention, considered with especial reference to embodiment in a machine such as that shown in Letters Patent to George Goddu, No. 1,030,775, granted 105 June 25, 1912, in which work-clamping pressure is applied yieldingly at the time the shoe operating instrumentalities become operative, important features of the invention consist in the organization by which 110

pressure applied upon the work is uniform over the widest range of thicknesses in the work supplied.

An important feature of the invention 5 is the provision of means for automatically adjusting the work support to variations in the thickness of the work practically simultaneously with the application of final clamping pressure thereon. This feature 10 adds greatly to the ease and rapidity of operation of the machine.

My invention contemplates also a novel 15 form of work support which is locked in work receiving position to enable the work to be readily positioned thereon. Before the machine is started the work support is instantaneously unlocked in order that the work measuring operation may take place, the construction and arrangement being 20 preferably such that the locking means is controlled by the mechanism for starting the machine in operation.

Other important features and objects of 25 the invention will appear from the following description and claims when considered in connection with the accompanying drawings.

In the drawings,

Fig. 1 is a side view partly in section showing the application of my invention to 30 a fastening inserting machine.

Fig. 2 is a front view partly in section of the automatic adjusting mechanism of the work support, and

Fig. 3 is a side view of the mechanism 35 shown in Fig. 2.

For the purposes of illustration, the invention is shown embodied in a fastening inserting machine of the type disclosed in said Letters Patent, the said machine comprising 40 fastening inserting mechanism indicated by reference character 4 having the usual work abutment 6 and work gage 8. Mounted in the frame 10 of the machine is the usual horn or jack shaft 12 which rests 45 at its lower end on a two-part lever 14, the connection between the jack shaft 12 and lever 14 comprising a slidably pivoted block 16, the construction of the lever and connection being exactly as shown in the patent to 50 Goddu No. 1,011,941, granted December 19, 1911, to which reference should be had for a detailed account of this part of the structure. Briefly, the mechanism for lifting the jack shaft 12 consists of the lever 14 already mentioned 55 to which there is pivoted at 18 the lower link 20 of a toggle comprising an upper link 22 pivoted to the lower end of a slide 24 which is reciprocable in a casing 26 fixedly secured to the machine frame. Slide 60 24 is locked to its casing or surrounding bracket by means disclosed in the last-mentioned patent whenever the toggle is broken to cause the work-releasing movement of the work support while the work is being fed. 65 Adjustably attached to the upper end of the

slide 24 is a rod 28 surrounded by a heavy spring 30 extending from the collar 32 on the rod 28 to a partition plate located at 34 in the machine frame. To make and break the toggle there is pivoted at 36 on the machine frame a bell crank lever 38 connected by a link 40 with the pivot 42 of the toggle links 20 and 22, said bell crank 38 being operated in properly timed relation with respect to the inserting mechanism by means 70 of a cam on the main shaft 44 through a link 46 attached to the upper arm of the bell crank. After the work has been placed upon the jack spindle 48 the same may be elevated to press the work against the abutment 6 by depressing a controller illustrated as a treadle 50, the latter being connected by a link 52 to a bell crank 54 pivoted at 56 and having a cam portion 58 which co-operates with a cam projection 60 on one part of 80 the two-part lever 14 to raise the jack shaft 12 as said part of the lever 14 moves with respect to the other part about the pivot 62 as a fulcrum, it being understood that the machine comes to rest with the toggle 20, 22 85 in the position shown in Fig. 1.

The construction and arrangement of the jack spindle is such that the work mounted thereon ordinarily just clears the abutment 6, that is, moves thereunder with space to 90 spare when the jack spindle is moved from front to rear in positioning the work under the abutment, so that a slight upward movement of the jack spindle brings the work in contact with the abutment after which said part of the lever 14 ceases to turn about 62 as a fulcrum and turns instead about pivot 64 in the block 16, thus raising the free end of the other part of the lever and through the toggle mechanism and rod 28 compressing the spring 30 and in this manner effecting final clamping pressure on the work. Following this, further or continued downward movement of the treadle 50 causes the actuation of the shaft 44, and hence of the 100 power means for operating the work support and the inserting mechanism, through the upward movement given to the rod 66 which controls the clutch starting mechanism on shaft 44, there being a yoke connection 68 105 between the rear end of the treadle 50 and the said rod 66. All of the mechanism thus far described will be found set forth in detail in the patent to Goddu No. 1,011,941, referred to above. A separate treadle 69 110 may be provided for starting the machine, this arrangement being such that the work support remains in lowered or work-receiving position while the fastening inserting mechanism only is operated.

Mounted upon the horn or jack shaft 12 is the work support mechanism shown in the present embodiment of the invention to comprise a jack spindle 48 pivoted on a transverse axis 70 to a plate 72 mounted to rock 130

on an axis at right angles to the first-mentioned axis, in a manner similar to that shown in the patent to Cuff, No. 919,424, granted April 27, 1909, and carried by a 5 slide 74 having convenient shoulders or projections 76 to which are attached the corresponding ends of two springs 78 preferably of the form shown in Fig. 1 of the drawings, the other ends of said springs being attached by screws 80 to a housing 82 fixedly secured to the lower end of a bracket 84 in which housing the plate 74 is slidably received. The housing 82 and bracket 84 constitute a supporting member for the plate 15 74 and the parts carried thereby. The plate or slide 74 is retained in its housing by means of a pin-and-slot connection indicated at 85, Fig. 2. Upon reference to Fig. 2 of the drawings it will be observed that the 20 plate 74 is provided with rack teeth 86 at its opposite edges, the rack teeth on one edge facing upwardly and those on the other edge downwardly. Mounted in the housing 82 are pawls 88 and 90 normally pressed into 25 engagement with the rack teeth on the slide-able plate by means of plungers 92 and 94, respectively urged into contact with the pawls by springs one of which is disclosed at 96. By means of the co-operating rack 30 and pawls the spindle 48 is locked in the housing 82 against movement in either direction relatively thereto. Mounted fixedly upon a short shaft 98 in the housing 82 is a cam plate 100 having cam portions 102 35 arranged to engage the pawls 88 and 90 to cause the same to be disengaged from the teeth 86 on plate 74, thus freeing the plate so that the springs 78 may carry said plate and the jack 48 upwardly to press the work 40 into yielding contact with the abutment 6. In order to rotate the cam plate 100 in the illustrative machine there is mounted fixedly on shaft 98 a ratchet wheel 104 with which there is engaged a pawl 106 pivoted 45 at 108 on an arm 110 mounted loosely on shaft 98, the said arm having pivoted thereto at 112 the rod 114 which extends downwardly and is connected to the outer end of treadle 50. An adjustable connection 115 is 50 provided between the rod 114 and treadle 50 by means of which the time of locking of the spindle to its supporting member may be varied slightly with respect to the movement of the lever 14 and thus determine ad- 55 justably the pressure on the work originating in spring 30. Obviously, upon depressing the treadle the arm 110 will be rotated about the shaft 98 moving the ratchet wheel 104 along with it until the pawl 106 engages 60 the cam surface 116 on the plate 118, the said cam surface acting to disengage pawl 106 from the ratchet wheel after having moved the latter through a distance equal to the length of a cam surface 102 on the 65 cam plate 100, the operation resulting in

disengaging the pawls 88 and 90 from the teeth 86 and then permitting them to re-engage the said teeth. As the pawl 106 is disengaged from the ratchet wheel 104 when the cam plate 100 has been moved the requisite distance, further movement of the treadle does not disturb the re-arranged pawls in their connection with the teeth on the plate 74. 70

The operation of this part of the mechanism may be briefly stated as follows: When the operative depresses treadle 50 the first part of the downward movement results in the rotation of the cam plate 100, thus unlocking the pawls 88 and 90 from engagement with the teeth 86 and permitting the springs 78 to carry plate 74 and the attached jack spindle 48 upwardly to press the work against the abutment 6. This operation of pressing the work against the abutment thus measuring the same takes place practically instantaneously and the pawls then re-engage the rack teeth, thus locking the plate 74 and its connected jack spindle 48 firmly and fixedly to the bracket 84 carried by the jack shaft 12. This operation of moving the jack spindle 48 upwardly and locking it with relation to the jack shaft 12 takes place in the first part of the depression of the treadle so that there is only a 90 slight upward movement of the lever 14 about fulcrum 62 before the described unlocking and relocking occurs, further depression of the treadle resulting in the turning of the lever 14 about pivot 64 to compress spring 30 and thus place the work under final clamping pressure backed by said spring 30. At the end of the downward movement of the treadle 50, the starting mechanism is actuated through the connecting rod 66 and the machine operates to insert fastenings in the work. During the operation of the machine a fastening is inserted in the work while it is held firmly pressed against the abutment, the jack spindle is then depressed through breaking of the toggle 20, 22 while the work is being fed, and the work again pressed against the abutment 6 through straightening of the same toggle 20, 22, thus clamping the work 100 while the next fastening is being inserted. It will be observed from the construction thus disclosed that the work is measured while the jack spindle is free to move upwardly under the action of springs 78 and 110 that after the work is measured the jack spindle is again locked fixedly to its supporting member 84 while pressure is placed upon the work during the further depression of the treadle. When one piece of work 115 has been operated upon, the treadle 50 is permitted to rise under the action of the spring 67 surrounding the rod 66, thus removing the cam 58 from supporting position beneath the lever 14 and permitting the 120 130

work support to drop into work receiving position. Since the spindle 48 is normally locked to its supporting member 82, 84, when the work support drops a considerable space is left between it and the work abutment. The work is then removed by pulling the jack spindle toward the operative and new work is placed upon the jack spindle which is then shoved rearwardly to bring the work beneath the abutment 6. When the treadle 10 is depressed the work support is automatically adjusted to the thickness of the work as above described. If, however, the work newly placed upon the jack spindle is much 15 thicker or higher than that before operated upon it may be necessary to unlock the jack spindle and plate 74 so that the jack spindle may be depressed against the action of the springs 78 in order that the work may be 20 shoved in under abutment 6. This is accomplished by a slight downward movement of the treadle just sufficient to cause the cam plate 100 to move the pawls outwardly from engagement with the teeth on plate 74. Under 25 these conditions, the jack spindle may then be depressed directly by the operative against the action of springs 78 to get the work positioned properly under abutment 6 and when this is accomplished the treadle is 30 further depressed to cause the regular operation of the machine.

Having fully described my invention, what I claim as new and desire to secure by Letters Patent of the United States is:

35 1. In a machine of the class described, a work support movable between work-receiving and work-clamping positions and normally locked in work-receiving position, manually operable means for moving the 40 support toward work-clamping position, and means for automatically adjusting the support to variations in the thickness of work and for locking said support in adjusted position preliminarily to the operation of 45 the machine.

50 2. In a machine of the class described, a work abutment, a work support movable between work-receiving and work-clamping positions, manually operated means for moving the support toward work-clamping position, power means for moving the work support toward and from said abutment, and means operatively connected to the power means for automatically adjusting 55 the support to variations in the thickness of the work.

60 3. In a machine of the class described, a work support movable between work-receiving and work-clamping positions and normally locked in work-receiving position, means for moving the support toward work clamping position, and means controlled by 65 said first-mentioned means for moving the work support into work clamping position and for locking it there.

4. In a machine of the class described, a work support movable between work-receiving and work-clamping positions and normally locked in work-receiving position, means for moving the support toward work-clamping position, and means, controlled by 70 said first-mentioned means and operating simultaneously therewith, for moving the work support into work-clamping position and for locking it there. 75

5. In a machine of the class described, a work support movable between work-receiving and work-clamping positions and normally locked in work receiving position, said work support being so mounted that it may 80 be readily depressed directly by the workman in placing work thereon thicker than that previously operated upon, means for moving the support toward work clamping position, and means for automatically adjusting the support, preliminarily to throwing the machine into operation, to ensure the application 85 of uniform pressure to the work.

6. In a machine of the class described, a work support movable between work-receiving and work-clamping positions, said work support being so mounted that it may be 90 readily depressed directly by the workman in placing work thereon thicker than that previously operated upon, manually operated means for moving the support toward work-clamping position, and means for automatically adjusting the support, preliminarily to throwing the machine into operation, to ensure the application of uniform 95 pressure on the work.

7. In a machine of the class described, a work support movable between work-receiving and work-clamping positions and normally locked in work-receiving position, means for yieldingly applying final clamping pressure to the work on the support, and means for adjusting the support automatically so that said final pressure is uniform, 105 independent of the thickness of the work. 110

8. In a machine of the class described, a work support movable between work-receiving and work-clamping positions, manually operated means for moving the support toward work-clamping position, spring means for then completing the upward movement of the work support to measure the work, and means for locking the work support after the measuring operation. 115

9. In a machine of the class described, a work support movable between work-receiving and work-clamping positions, manually operated means for moving the support toward work-clamping position, and means, controlled by the first-mentioned means, for automatically measuring the work preliminarily to further operation thereon. 120

10. In a machine of the class described, a work support movable between work-receiving and work-clamping positions, manually 125 130

operated means for moving the support toward work-clamping position, spring means, operable simultaneously with the first-mentioned means, for completing the upward movement of the work support to measure the work, and means for locking the work support after the measuring operation.

11. In a machine of the class described, a work abutment against which the work may be clamped, a work support movable between work-receiving and work-clamping positions, means for moving the work support toward said abutment, and means constructed and arranged to operate simultaneously with the first mentioned means for pressing the work on the support yieldingly against the abutment.

12. In a machine of the class described, a work support normally locked in position on the machine, manually operated means for moving the support, a spring for moving the support relatively to the manually operated means, and locking means operative to release said support to the action of the spring and to lock said support at the termination of its movement by the spring.

13. In a machine of the class described, a work abutment against which the work may be clamped, a work support movable between work-receiving and work-clamping positions, means for moving the work support toward said abutment, power means for moving the work support toward and from said abutment, and means separate from and operating simultaneously with the first-mentioned means for pressing the work on the support yieldingly against the abutment.

14. In a machine of the class described, a work abutment against which the work may be clamped, a work support movable between work-receiving and work-clamping positions, manually operated means for moving the work support toward the abutment comprising a horn or jack shaft on which the work support is mounted, and means for moving the work support automatically with respect to and in the direction of the length of said shaft during the operation of the first-mentioned means.

15. In a machine of the class described, a work abutment against which the work may be clamped, a work support movable between work-receiving and work-clamping positions, manually operated means for moving the work support toward the abutment comprising a horn or jack shaft on which the work support is mounted, and means for moving the work support automatically with respect to said shaft during the operation of the first-mentioned means, and for locking the support to said shaft at the end of its movement, said locking means being under the control of the operator.

16. In a machine of the class described, a

work support normally locked in position on the machine, a spring for moving said support, and manually controlled locking means operative to release said support to the action of the spring and to lock said support at the termination of its movement by the spring.

17. In a machine of the class described, a work abutment against which the work may be clamped, a work support movable between work-receiving and work-clamping positions, manually operated means for moving the work support toward said abutment constructed and arranged to apply final work-clamping pressure, and means operating simultaneously with the first-mentioned means to measure the work.

18. In a machine of the class described, a work abutment against which the work may be clamped, a work support movable between work-receiving and work-clamping positions, manually operated means for moving the work support toward said abutment constructed and arranged to apply final work-clamping pressure, and means operating automatically to measure the work preliminarily to the application of said pressure.

19. In a machine of the class described, a work abutment against which the work may be clamped, a work support movable between work-receiving and work-clamping positions, manually operated means for moving the work support toward said abutment constructed and arranged to apply final work-clamping pressure, and automatically operated means for measuring the work and for locking the work support to said manually operated means.

20. In a machine of the class described, a work abutment against which the work may be clamped, a work support movable between work-receiving and work-clamping positions, manually operated means for moving the work support toward said abutment constructed and arranged to apply final work-clamping pressure, power means for moving the work support toward and from the abutment, and means operating automatically to measure the work preliminary to the operation of said power means.

21. In a machine of the class described, a work support movable between work-receiving and work-clamping positions, said support comprising a jack spindle and a supporting member therefor normally in locked relation to each other, means for starting the machine, and means controlled by said starting means for causing relative movement between the jack spindle and its supporting member.

22. In a machine of the class described, a work support movable between work-receiving and work-clamping positions, said support comprising a jack spindle and a supporting member therefor normally in locked

- relation to each other, means for starting the machine, and means controlled by said starting means for locking the spindle to its supporting member.
- 5 23. In a machine of the class described, a work abutment, a work support normally spaced from said abutment and movable between work-receiving and work-clamping positions, said support comprising a jack 70
10 spindle and a supporting member therefor, means for starting the machine, means for automatically moving the spindle toward work-clamping position, and means for locking the spindle to its supporting member.
- 15 24. In a machine of the class described, a work abutment, a work support normally spaced from said abutment and movable between work-receiving and work-clamping positions, said support comprising a jack 75
20 spindle and a supporting member therefor, manually operable means for positively moving the spindle toward work-clamping position, and means controlled by said first-mentioned means for yieldingly moving the
25 spindle in the same direction.
- 25 25. In a machine of the class described, a work support movable between work-receiving and work-clamping positions and normally in work-receiving position, said support comprising a jack spindle and a supporting member therefor, manually operable means for moving the spindle and its supporting member toward work-clamping position, and means for moving the spindle 80
30 automatically relatively to its supporting member and into final work-clamping position.
- 35 26. In a machine of the class described, a work support movable between work-receiving and work-clamping positions and normally in work-receiving position, said support comprising a jack spindle and a supporting member therefor, means for starting the machine, and means controlled 85
40 by said starting means for moving the spindle automatically relatively to its supporting member and for locking it in proper relation thereto.
- 45 27. In a machine of the class described, a work support movable between work-receiving and work-clamping positions, said support comprising a jack spindle and a supporting member therefor normally in locked relation to each other, and means 90
50 for moving the spindle automatically relatively to its supporting member and for locking it against movement in either direction relatively to the supporting member.
- 55 28. In a machine of the class described, a work abutment, a work support normally spaced from said abutment and movable between work-receiving and work-clamping positions, said support comprising a jack spindle and a supporting member therefor, means operative for pressing the spindle to 95
60
65
ward work-clamping position, a treadle and means intermediate between the jack spindle and its supporting member and controlled by said treadle for locking the jack spindle to its supporting member.
29. In a machine of the class described, a work support movable between work-receiving and work-clamping positions, said support comprising a jack spindle and a supporting member therefor normally in locked 70
75 relation to each other, a treadle, means controlled by said treadle for locking the spindle to its supporting member, and means for causing relative movement between the spindle and its supporting member.
30. In a machine of the class described, a work support movable between work-receiving and work-clamping positions, said support comprising a jack spindle and a supporting member therefor, a treadle, 80
85 means for moving the spindle toward work-clamping position, means for locking the spindle on its support, and a rotary cam operable by said treadle for controlling said locking means.
31. In a machine of the class described, a work support movable between work-receiving and work-clamping positions, said support comprising a jack spindle and a supporting member therefor normally in locked 90
95 relation to each other, means operative automatically for moving the spindle toward work-clamping position and automatic means controlled by said first-mentioned means for yieldingly moving the spindle in 100
100 the same direction.
32. In a machine of the class described, a work support movable between work-receiving and work-clamping positions, manually operated means for moving the 105
110 work support constructed and arranged to apply final work-clamping pressure, and means operating simultaneously with the first-mentioned means to adjust the work support to work of varying thickness.
33. In a machine of the class described, a work support movable between work-receiving and work-clamping positions, manually operated means for moving the work support constructed and arranged to 115
120 apply final work-clamping pressure, and automatic means operating simultaneously with the first-mentioned means to ensure the application of uniform pressure to pieces of work of various thicknesses.
34. In a machine of the class described, a work support movable between work-receiving and work-clamping positions, manually operable means for moving the work support to work-clamping position, and cam 125
130 controlled means for locking the support in work-receiving position.
35. In a machine of the class described, a work support movable between work-receiving and work-clamping positions,

means for moving the work support to work-clamping position, means carried in part by the work support for locking the support in work-receiving position, and starting mechanism arranged to control said locking means.

36. In a machine of the class described, a work support movable between work-receiving and work-clamping positions, means for periodically depressing the work support from work clamping position, means separate from the depressing means for moving the work support constructed and arranged to apply final work-clamping pressure, and automatic means operating simultaneously with said moving means to ensure the application of uniform pressure to pieces of work of various thicknesses.

37. In a machine of the class described, a jack shaft, a work support movable from work receiving to work clamping position, means for locking the work support to the jack shaft, and manually controlled means for unlocking the work support from the jack shaft upon movement of the support from work receiving toward work clamping position.

38. In a machine of the class described, a work support movable from work receiving to work clamping position, a member to which said work support is normally locked in work receiving position, manually operable means for moving the support toward work clamping position, and means for unlocking the support from said member upon movement of the support toward work clamping position and for locking the support to said member upon the arrival of the support at work clamping position.

40. In a machine of the class described, a work support movable from work receiving to work clamping position, manually operable means for moving the work support toward work clamping position, and means for moving the support relatively to the manually operable means upon movement of the support toward work clamping position.

40. In a machine of the class described, a work support movable from work receiving to work clamping position, a supporting member to which the work support is normally locked, manually operated means for moving the supporting member, and means for moving the work support relatively to its supporting member to measure the work upon movement of the supporting member by the manually operable means.

41. In a machine of the class described, a work support movable from work receiving to work clamping position, a supporting member to which the work support is normally locked, manually operated means for moving the supporting member to elevate the work support to work clamping position, means for moving the work support relatively

to its supporting member to measure the work, and means for securing the work support to its supporting member for movement therewith.

42. In a machine of the class described, a work support movable from work receiving to work clamping position, means for periodically depressing the work support from work clamping position constructed and arranged to compensate for variations in thickness of the work, and means distinct from the depressing means for locking the work support in work receiving position.

43. In a machine of the class described, a work support movable from work receiving to work clamping position, means for periodically depressing the work support from work clamping position, and means for locking the work support in work receiving position, constructed and arranged to be operative during a complete cycle of operation of the depressing means.

44. In a machine of the class described, a work support movable from work receiving to work clamping position, means for moving the work support toward work receiving position, means for periodically depressing the work support from work clamping position, and means separate from the first mentioned moving means for automatically moving the work support relatively to the depressing means.

45. In a machine of the class described, a work support movable from work receiving to work clamping position, a supporting member therefor, means for depressing the supporting member to move the work support from work clamping position, means for locking the work support to the supporting member during a complete cycle of operations of said depressing means, and means for moving the work support relatively to its supporting member upon movement of the support from work receiving to work clamping position.

46. In a machine of the class described, a work support movable from work receiving and work clamping positions, a supporting member therefor, means for depressing the supporting member to lower the work support from work clamping position, connections between the work support and its supporting member for locking the work support to its supporting member during a complete cycle of operations of the depressing means, and means for moving the work support relatively to the supporting member upon movement of the support from work receiving to work clamping position.

47. In a machine of the class described, a work support movable from work receiving to work clamping position, a supporting member to which the work support is normally locked, means for depressing the supporting member to lower the work support

from work clamping position, and means interposed between the work support and the supporting member for effecting relative movement of the support and the supporting member upon movement of the support from work receiving to work clamping position.

48. In a machine of the class described, a work support movable from work receiving to work clamping position, a supporting member therefor, said work support and supporting member being constructed and arranged for relative movement in accordance with the thickness of the work upon movement of the work support to work clamping position, means for locking the work support to the supporting member in work receiving position, and manually operable means for moving the work support from work receiving to work clamping position.

49. In a machine of the class described, a work support, a supporting member therefor, a yielding connection between the work support and the supporting member, operator controlled means operable on the supporting member to apply final work clamping pressure to the work support, means for locking the work support to the supporting member, and means operated by said operator controlled means for controlling said locking means.

50. In a machine of the class described, a work support movable from work receiving to work clamping position, a supporting member therefor, means for moving the supporting member to raise the work support, and means for locking the work support to its supporting member, constructed and arranged to permit relative movement of the work support and the supporting member when the work support is raised and to secure the support in fixed relation to the supporting member during the reverse movement of the supporting member.

45. 51. In a machine of the class described, a work support movable between work receiving and work clamping positions, a member operable in one direction to move the work support from work clamping to work receiving position and in another direction to cause reverse movement of the support to work clamping position, means for normally locking the support to said member when in work receiving position, constructed and arranged to be operative during the entire movement of said member in the first-mentioned direction and during the latter part of its reverse movement, and means for moving the support relatively to said member intermediate between the movements of said member in said first-mentioned direction.

52. In a machine of the class described, a work support movable between work receiving and work clamping positions and nor-

mally locked in work receiving position, manually controlled means for moving the support toward work clamping position, and mechanism operating in timed relation to the means for moving the support toward work clamping position for adjusting the support to compensate for variations in the thickness of the work and for locking said support in adjusted condition preliminarily to the operation of the machine.

53. In a machine of the class described, a work abutment, a work support movable between work receiving and work clamping positions, means for moving the support toward work clamping position, power-operated means for moving the work support toward and from said abutment during the operation of the machine to facilitate the feeding of the work, and mechanism operatively connected to the power-operated means and arranged to operate in timed relation to the moving of the support toward work clamping position for adjusting the support to compensate for variations in the thickness of the work.

54. In a machine of the class described, a work support movable between work receiving and work clamping positions, and normally locked in work receiving position, said work support being so mounted that it may readily be depressed directly by the operative when necessary in placing work thereon, means for moving the support toward work clamping position, and mechanism for adjusting the support preliminarily to throwing the machine into operation to insure the application of uniform pressure to the work.

55. In a machine of the class described, a work support movable between work receiving and work clamping positions and normally locked in work receiving position, means for yieldingly applying final pressure to the work on the support, and mechanism for adjusting the support arranged to operate prior to the application of final pressure to the work to insure uniform final pressure independent of the thickness of the work.

56. In a machine of the class described, a work support movable from work receiving to work clamping position, a member to which said work support may be alternatively locked in work receiving and in work clamping position, a controller movable in a limited path to initiate and terminate operation of the machine, and means operated in accordance with the position of said controller for locking the work support to said member when the controller is at either end of its path of movement and releasing the work support from said member when the controller is at an intermediate portion of its path of movement.

57. In a machine of the class described, a jack shaft, a work support carried thereby

and movable from work receiving to work clamping position, means for locking the work support to the jack shaft, a controller movable in a limited path alternatively to 5 initiate and terminate operation of the machine, and mechanism constructed and arranged to lock the work support to the jack shaft in work receiving or work clamping position according as said controller is at one end or the other of its path of movement and to release the work support from the jack shaft to permit relative movement of said work support and jack shaft when the controller is at an intermediate portion 10 of its path of movement.

58. In a machine of the class described, a work support movable from work receiving to work clamping position, means operable to lock the work support alternatively 20 in work receiving and work clamping position, a controller for the machine movable through a limited path, and means controlled by the movement of said controller for operating the locking means to lock the 25 work support in work receiving or in work clamping position according as the controller is at one end or the other of its path of movement and for releasing the work support from the locking means when the controller 30 is at an intermediate portion of its path of movement.

59. In a machine of the class described, a work support movable between work receiving and work clamping positions, 35 means comprising a spring for moving the work support toward work clamping position, means carried in part by the work support for locking the support against movement by said spring, starting mechanism, 40 and a treadle having connections for controlling the starting mechanism and the locking means.

60. In a machine of the class described, a work support movable between work receiving and work clamping positions, a 45 spring for moving the work support toward work clamping position, a latch comprising a pawl and a toothed member, one of which is carried by the work support, co- 50 operating to hold the work support against movement by said spring, and a treadle having connections for controlling said pawl.

61. In a machine of the class described, a work support movable between work receiving and work clamping positions, a 55 spring for moving the work support toward work clamping position, a latch comprising a pawl and a toothed member, one of

which is carried by the work support, co-operating to lock the work support against movement by said spring, and a treadle having connections for releasing the pawl from engagement with the toothed member thus permitting the spring to move the work support. 60

62. In a machine of the class described, a work support movable between work receiving and work clamping positions, a spring for moving the work support to work clamping position, a latch comprising 70 a pawl and a toothed member, one of which is carried by the work support, co-operating to lock the work support against movement by the spring, and a manually controlled cam member for moving the pawl from locking position thus permitting the spring to move the work support. 75

63. In a fastening inserting machine, a work support movable between work receiving and work clamping positions, a spring 80 for applying work clamping pressure and serving as an abutment during the insertion of fastenings, power-operated means for latching the work support in work receiving position, and a manually operable 85 controller for unlatching the work support so that it may move to work clamping position.

64. In a machine of the class described, a work support movable between work receiving and work clamping position, a latch member carried by the work support, a 90 spring tending to move the work support to work clamping position, a manually operable controller movable to start and stop 95 the machine, and means connected to and operable by the controller to cause the latch member to latch the work support in work receiving position when the controller is in its stopping position. 100

65. In a fastening inserting machine, a work support movable between work receiving and work clamping position, a spring operable to apply clamping pressure to the work and serving as an abutment during the insertion of the fastenings, a controller movable to start and stop the machine, and a latch thrown into and out of operation by the movement of the controller to latch the work support in work 105 receiving position when the controller is in stopping position. 110

In testimony whereof I have signed my name to this specification.

FRED L. MACKENZIE

Certificate of Correction.

It is hereby certified that in Letters Patent No. 1,417,540, granted May 30, 1922, upon the application of Fred L. Mackenzie, of Beverly, Massachusetts, for an improvement in "Work Supports," errors appear in the printed specification requiring correction as follows: Page 3, line 5, for the word "convenient" read *conveniently*; page 7, line 112, claim 46, for the word "from" read *between*; and that the said Letters Patent should be read with these corrections therein that the same may conform to the record of the case in the Patent Office.

Signed and sealed this 29th day of August, A. D., 1922.

[**SEAL.**]

KARL FENNING,

Acting Commissioner of Patents.
